LETTER-BOMB DETECTOR

Herbert S. Kulik and Jacob Schachter, both of 100
Ricefield Lane, Hauppauge, N.Y. 11787

Filed Mar. 30, 1973, Ser. No. 346,414

Term of patent 14 years

Int. Cl. D10—05

U.S. Cl. D52—1 R

FIG. 1

FIG. 4

FIG. 2

FIG. 5

FIG. 3

FIG. 1 is a top plan view of a letter-bomb detector showing my new design;

FIG. 2 is a front elevational view thereof, the rear being substantially a mirror image thereto;

FIG. 3 is a bottom plan view thereof;

FIG. 4 is a left side elevational view thereof; and

FIG. 5 is a right side elevational view thereof.

We claim:

The ornamental design for a letter-bomb detector, substantially as shown and described.
